UNITED STATES PATENT OFFICE

HENRY STARNES, OF HOUSTON, TEXAS, ASSIGNOR TO DUNCAN COFFEE COMPANY, OF HOUSTON, TEXAS, A CORPORATION OF TEXAS

DESIGN FOR A BAG OR SIMILAR CONTAINER

Application filed June 27, 1931. Serial No. 40,341. Term of patent 14 years.

To all whom it may concern:

Be it known that I, HENRY STARNES, a citizen of the United States, residing at Houston, in the county of Harris and State of Texas, have invented a new, original, and ornamental Design for Bags or Similar Containers, of which the following is a specification, reference being had to the accompanying drawings, forming part thereof.

In these drawings, Fig. 1 is a front elevation of a container showing my new design; and Fig. 2 is a rear elevation thereof.

I claim:

The ornamental design for a bag or similar container as shown.

HENRY STARNES.
